UNITED STATES PATENT OFFICE

RALPH C. SEYMOUR, OF LARCHMONT, NEW YORK, ASSIGNOR TO GOSS PRINTING PRESS COMPANY, A CORPORATION OF ILLINOIS.

SHEET-HANDLING MACHINE.

1,173,878.

Specification of Letters Patent. Patented Feb. 29, 1916.

Application filed June 17, 1913. Serial No. 774,098.

To all whom it may concern:

Be it known that I, RALPH C. SEYMOUR, a citizen of the United States, and a resident of Larchmont, in the county of Westchester and State of New York, have invented certain new and useful Improvements in Sheet-Handling Machines, of which the following is a specification.

The invention relates to sheet handling machinery, and more especially to machines for collecting and folding sheets cut from a web.

The objects and advantages of the invention will in part be set forth hereinafter, and will in part be obvious herefrom, and such objects and advantages are attained or effectuated by the means or instrumentalities set forth in the appended claims.

The invention consists in the novel parts, constructions, arrangements, combinations and improvements herein shown and described.

The accompanying drawings, referred to herein and forming a part hereof, illustrate one embodiment of the invention, the same serving in connection with the description herein to explain the principles of the invention.

Of the drawings: Figure 1 is an elevation, with the front frame removed, of a machine constructed in accordance with the principles of the invention; Fig. 2 is a view looking at Fig. 1 from the right; Fig. 3 is a view looking at Fig. 1 from the left; Fig. 4 is a fragmentary view of a development of the plate cylinder of the press by which the web α of Fig. 1 is printed, the length of the plates being arranged longitudinally of the plate or form cylinder; Fig. 5 shows two successive sheets cut from the web with the manner of folding when printed by the plate cylinder with the plates arranged as in Fig. 4; Fig. 5^a shows the two sheets of Fig. 5 inset and partly folded; Fig. 6 is a fragmentary development of the plate or form cylinder of the press, by which the web α is printed, with the length of the plates arranged about or transversely of the form cylinder; Fig. 7 shows two successive sheets cut from the web with the manner of folding when printed by the plate cylinder with the plates arranged as in Fig. 6; and Fig. 7^a shows the four sheets of Fig. 7 inset and partly folded.

Referring to the accompanying drawings,

illustrating by way of example one embodiment of the invention, a mechanism is shown adapted to receive a running web which has been perfected in a rotary perfecting printing press. The web will be regarded as coming from the printing press at the upper left hand end of Fig. 1, and as being fed forward by suitable devices such as the roller 1 and the tape 2 running thereover, and also over rollers 3, 4 and 5.

The invention includes means for supplying and directing sheets of different sizes to a plurality of correspondingly sized collecting devices and to folding devices which are adapted to fold the different sizes of sheets in such manner as to provide all cut edges excepting at the fold line.

As embodied, the sheets are collected and then folded. Further, as embodied, the sheets are cut in different lengths from the running web and the sheets as cut and supplied are directed to one set or another of the subsequent devices, whereby the sheets are so folded or collected and folded that all edges except that at the back or fold are free or cut. Thus the product of the machine in its various sizes in complete, folded and openable without being taken to and run through a trimming machine.

In the embodied form, as already indicated, the mechanism is adapted to receive the running and perfected web α from the printing press, and means are provided for cutting from the web α sheets of different lengths. The embodied form of sheet cutting means comprises shafts 3' and 4', carrying, respectively, a series of disks 5' and a series of disks 6. Mounted on the disks 5', by means of slotted web 10, arranged along the disks 5', is a cutter member 7, said cutter member 7 being adjustable or removable by means of suitable devices, such as the bolt and slot connection 9 between the cutter 7 and the web 10. A co-operating cutting member 8 is carried by a web 11, extending longitudinally along the disks 6. This cutter 8 is also adjustably and removably mounted by suitable means such as bolt and slot 9. As the disks 5' and 6 rotate, cutters 7 and 8 co-operate to cut the web in a well known manner.

Another set of co-operating web cutting devices are provided in the embodied form, including a cutter member 12, longitudinally arranged along web 14 extending between

the disks 5'. The complementary and co-operating cutter member 15 is likewise carried by a web 17 extending longitudinally between the disks 6. The cutters 12 and 15 5 may also be adjustably or removably mounted if desired, by any suitable means as for instance, by a bolt and slot connection, as already described.

By removing one set of the cutter members, as for example, cutters 7 and 8, a sheet 10 will be cut off a length substantially equal to the circumference of the disks 5' and 6. When both sets of cutter members are used, shorter length sheets are cut off from the 15 web and when the cutter members are diametrically positioned with respect to the disks 5' and 6, twice the number of sheets are cut off, each sheet being half the length of the sheets cut off when but one pair of co- 20 operating cutter members are used.

Means are provided for directing the sheets of different sizes to the subsequent mechanisms so as to procure the desired product and in the embodied form thereof 25 a series of throat bars 20 are mounted on a rod 21, and an opposing set of throat bars 22 suitably mounted on a rod 23. Mounted below the cutting devices already 30 described are a set of rotating disks or rollers 24, carried on shaft 28, operating against a similar set of disks or rollers 25 carried on shaft 29. The end of the web is received between the two sets of disks or rollers 24 and 25 and is directed forward 35 through the machine. These disks or rollers, if desired, may be provided with cut away portions 18 and 19 which operate to give a prompt and full release to the tail of the sheet.

40 In the embodied form there are also provided a set or series of rollers or disks 26, carried on shaft 30, co-operating with a complementary or corresponding set 27 of such rollers or disks, carried on shaft 31, which 45 serve the same purpose as the other set of rollers or disks. If desired one set of opposed rollers or disks may be rendered inactive in any suitable manner. As embodied, the lower disks 26 and 27 are so 50 constructed. For this purpose, the shaft 30 has slideable bearings in the machine frame, of suitable form, said bearings being adjustable by means of threaded rods 32. The shaft 31 is similarly mounted, and is provided 55 with a similar threaded rod 33. Springs 34 press the opposed disks together when in operative position with the web. These disks 26 and 27 are also shown with cut away portions, which give a prompt 60 release for the tail of the sheet.

The sheets, cut to one length or the other, are received from the sheet directing and forwarding means and are folded so as to provide all cut sheets except at the fold, as 65 already described. In accordance with one

feature of the invention each length or size of sheet is or may be collected or associated prior to folding to give a larger product, cut and folded as above indicated.

In the embodied form of means, a collecting cylinder 35 is provided for the longer sheets, mounted upon a suitable shaft 36. Said cylinder is provided with sheet taking grippers 38 adapted to receive the lead end of the web α , or of the severed sheet, at the instant it is severed from the web or just subsequently thereto. The form of folding means for the larger sheets, as embodied, folds transversely of the run of the web or of the length of the sheets as cut from the web, and suitable means are provided for this purpose. As embodied, the cylinder 35 is provided with a folding blade 39, which folding blade co-operates with a series of traveling folding jaws 40, adapted to fold and carry away the folded sheet or group of sheets to delivery. In the embodied form the jaws 40 are mounted on a cylinder or series of disks 41 rotating with and mounted upon the shaft 42. The cylinder 41 is adapted to deliver the sheets to any suitable delivery device, as for example a traveling pocket delivery 43 comprising a suitable carrier 44 with divisions 45, and traveling over rollers 46, or any other suitable form of delivery mechanism 95 may be provided.

A suitable stripping device, of any approved or known form, may be employed to insure the folded sheets being delivered 100 from the folding jaws at the proper time and place. The cylinder or disk 41, if desired, may be cut away or otherwise constructed to clear gripper or folding blade, or both, on cylinder 35, as shown at 47.

The cylinder 35 may be a collecting cylinder, and when so used, the gripper 38 will open to receive the lead end of the second sheet upon the corresponding end of the first sheet, and the folding blade and folding jaws will be correspondingly timed so as to fold off the complete group of sheets when collected. A spring pressed roller 57 mounted on a suitable arm may be utilized to hold the sheets upon cylinder 35 while 115 the gripper is taking the second sheet. The particular actuating and timing mechanisms are not shown, as these in themselves are at present known in the art.

There are likewise provided by the invention means for receiving the shorter sheets from the sheet directing and forwarding means, and for folding these so as to give all cut edges except at the fold. In accordance with one feature of the invention, furthermore, means are provided for collecting a plurality of shorter sheets arranged in series about the cylinder, or a plurality of groups of sheets so arranged, and co-operating with such collecting de- 125 130

vices, means for folding each group of collected or associated sheets after it is completed.

In the embodied form thereof, a cylinder 50 is provided mounted upon a suitable shaft 51. The cylinder 50 is provided with a plurality of grippers each adapted to hold one or more sheets upon the surface of the cylinder 50 and to discharge its sheet or group of sheets at the proper time. As shown, cylinder 50 is provided with three such sets of grippers, marked 52, 53 and 54, respectively. These grippers are likewise provided with suitable actuating and timing devices so that a plurality of sheets may be successively taken by each of the grippers 52, 53 and 54 and thus be collected or associated into a group and so collected or associated sheets then discharged together to the folding devices to be folded thereby. Such actuating and timing devices are not illustrated, as various forms thereof are at present known in the art. The cylinder 50 is shown with cut away portions 55 to afford clearance for grippers 38. Means are provided for directing the sheets from the cylinder 50 to the folder, and as embodied such means comprises strippers 56, and a series of top guides 58 and a corresponding series of bottom guides 59, downwardly inclined toward the folder, a series of rollers or disks 60 are provided which will bear on the sheets and when taken off by the stripper 56 will serve to forward the sheets forward along the runway or pathway between guides 58 and 59.

As embodied the folding devices give a longitudinal fold, that is, a fold lengthwise of the run of the sheet as it is run into the folder.

The embodied form of folding means comprises a set of folding rollers 64 and 65, and a folding blade 66, suitably mounted upon swinging arms 67 adapted to fold the sheets into the bite of the folding rollers. The folding rollers are mounted on shafts 61 connected and driven together by gears 62. One of these shafts is driven by a bevel gearing 63 from a shaft 68. A suitable stop 50 70 positions the sheets for folding. The folded sheets are delivered into a suitable receptacle, such as 71.

In accordance with one feature of the invention and in connection with the means for folding one length of sheets in one direction and the other length of sheets in the other direction, that is, giving a transverse fold to one length of sheets and a longitudinal fold to the other length of sheets, the sheet receiving or collecting devices are given different relative proportions with respect to the plate cylinder of the printing press. By this means the plates may be put on the form cylinder of the printing press either along or around the form cyl-

inder, and in the one case the sheets will be run to the one folder and previously through the corresponding collecting mechanism, or to the other folder and previously through the collecting mechanism corresponding to such other folder.

It will thus be seen that in each case the fold is properly positioned with respect to the printed pages upon the sheets, and all the other edges of the product are cut, and there is no necessity for trimming the edges.

By way of example and to illustrate the operation of the mechanism as shown and described, the cutting cylinders or disks 5, 6 may be regarded as half the diameter of 30 the plate cylinder 72, and the cylinder 35 as likewise being of half the diameter of the plate cylinder 72 and as collecting two successive sheets as cut from the web π , as shown in Fig. 5. In this case the printing plates are arranged with the length of the page lengthwise of, or along the form cylinder and four pages around the cylinder and as many pages along the cylinder, as may be desired. The printed pages would be arranged or located with their length across the web.

The cutting cylinders in such case would use but one set of cutters and make a cut between every second page (considering one side of the web only) and lengthwise of the pages. The cylinder 41 is shown of twice the diameter of cylinder 35 and would thus fold off two sheets at every revolution or it could be reduced to one-half its present 100 diameter and fold off two sheets at every second revolution. The cylinder 35 then collects two sheets, each having two pages on each side, and thus brings together the plates or pages once around the plate cylinder and folds them together once continually, bringing them together page after page, or as a signature, with all the edges properly cut. The upper set of forwarding rollers 24, 25 would be used, and the lower 110 set 26, 27 could be used or put out of operation.

Further by way of example and in connection with the description of the operation of the illustrated and described mechanism, the plates may be regarded as arranged with the length of the page around the form cylinder, instead of lengthwise thereof, as previously described. In each case it has been assumed that there are four plates around the form cylinder. In this case, the four sets of cutters would be used and a transverse cut made in the web between every page and the length of the printed pages extends along the web. If the web be more than two pages wide slitters could be used or several separate webs could be run side by side. The two sets of forwarding rollers would be used to insure the forwarding of the sheets in proper time,

the sheets always being in the bite of at least one set of forwarding rolls until taken by the grippers on the collecting cylinder.

The collecting cylinder 50 is three sheet lengths around, and thus the fourth sheet is collected on top the first, and so on, in a well known manner. When the four sheets of four pages each are collected or associated on cylinder 50, the stripper 60 directs the group of sheets into the pathway to the folder. The sheets are stopped and registered by stop 70 and are then folded by blade 66 into the bite of folding rollers 64 and 65 and the folded signature drops 10 into the receptacle. The fold is along the web and also along or between the pages, and all the edges are free or cut, except the fold at the back without the use of a trimmer. The parts would be so positioned 15 or timed that the lead ends of the sheets would come to the grippers of either cylinder 35 or 50.

Referring to Fig. 4, the plate cylinder, or rather the development thereof, is indicated 25 by reference numeral 72 and the plates thereon by 73. The length of the page of the plates is in the direction of the arrows in Fig. 4. Such a press is usually a rotary perfecting press.

Fig. 5 represents a single width web, or a slit portion of a wide web, which has been cut into successive sheets *y* and *z*. After being printed by a series of plates around the cylinder 72, and with four plates around the 30 form cylinder the two sheets would represent the impression of one complete rotation of the form cylinder 72. The web is cut between every second page, considering one face of the web, as at 76 in Fig. 5, and the sheets *y* and *z* would be associated or collected upon the cylinder 35. When so associated or collected, the folding blade 39 and jaws 40 would make a fold along the broken lines 77, thus completing the signature.

In Fig. 6 the plate cylinder 72, or the development thereof, is shown with plates 78 thereon, the long way of the page being represented by the arrows.

In Fig. 7 a section of the web is shown 50 cut into successive sheets *s*, *t*, *v*, *w* and represents an impression once around the form cylinder 72, the long ways of the page being represented by the arrows. The location of the cuts is indicated by reference numeral 79, and the cuts are twice as frequent as in the web shown in Fig. 5. These pages are collected upon the collecting cylinder 50, in the usual manner of the three-way collecting cylinder. The collected or associated sheets then receive their fold along the broken line 80, thus completing the 55 signature.

If a web wider than two pages is used, or if a plurality of webs are run side by side in a wide machine, a corresponding 60

number of folders could be used, and when necessary a number of slitters would be used at convenient points. Thus a single press could be used to print two publications of different sizes, and the sheets or pages of either size collected or associated and folded with all edges open or uncut, and with the 70 signatures ready to be collected.

It will be understood that the objects and advantages enumerated together with other 75 objects and advantages are realized by my invention and its embodiment.

The invention in its broader aspects, is not limited to the particular constructions shown, nor to any particular constructions 80 by which it has been or may be carried into effect, as many changes may be made in the construction without departing from the main principles of the invention and without sacrificing its chief advantages. 85

The swinging arms 67, which carry the folding blades, are shown pivoted at 81 on the machine frame. The tails of the members 67 are shown bearing on operating cams 83 to which they are held by springs 82. 90

What I do claim as my invention and desire to secure as Letters Patent, is:—

1. A sheet handling machine including in combination means for cutting a web into sheets of different lengths, means for directing said sheets along a path, a plurality of folding mechanisms, and means for directing sheets of one length from said pathway to one of said folding mechanisms and for directing sheets of another length to another 100 of said folding mechanisms. 95

2. A sheet handling machine including in combination means for cutting a web into sheets of different lengths, means for directing said sheets along a path, a plurality of folding mechanisms, one folding mechanism being located to one side of said pathway and another folding mechanism being located to another side of said pathway, and means for directing sheets of one length 110 from said pathway to one of said folding mechanisms and for directing sheets of another length to another of said folding mechanisms. 110

3. A sheet handling machine including in combination means for cutting a web into sheets of different lengths, means for directing said sheets along a path, a plurality of folding mechanisms, and means for directing sheets of one length from said pathway to one of said folding mechanisms and for directing sheets of another length to another of said folding mechanisms and collecting means for sheets of one of said lengths between said cutting mechanism and the folding mechanism for said sheets. 120

4. A sheet handling machine including in combination means for cutting a web into sheets of different lengths, means for directing said sheets along a path, a plurality of 130

- 5 folding mechanisms, and means for directing sheets of one length from said pathway to one of said folding mechanisms and for directing sheets of another length to another of said folding mechanisms and devices for collecting either length of sheets after cutting and before folding
- 10 5. A sheet handling machine including in combination means for cutting a web into sheets of different lengths, means for directing said sheets along a path, a plurality of folding mechanisms, and means for directing sheets of one length from said pathway to one of said folding mechanisms and for
- 15 15 directing sheets of another length to another of said folding mechanisms, collecting means for sheets of one length between said cutting means and the folding mechanism for sheets of said length, and collecting means for sheets of another length between said cutting means and the folding mechanism for sheets of said length.
- 20 6. A sheet handling machine including in combination means for cutting a web into longer and shorter sheets, means for associating a larger number of the shorter sheets and means for folding short sheets in one direction, and means for folding the longer sheets in another direction.
- 25 30 7. A sheet handling machine including in combination means for cutting a web into longer and shorter sheets, means for associating a proportionally larger number of the shorter sheets and means for folding short sheets in one direction and means for folding the longer sheets in another direction.
- 35 40 8. A sheet handling machine including in combination means for directing sheets of various lengths, collecting devices adapted to collect a plurality of shorter sheets, and means for folding the various sizes of sheets including the collected sheets to give all cut edges except at the fold.
- 45 45 9. A sheet handling machine including in combination means for directing sheets of various lengths, collecting devices adapted to collect a plurality of shorter sheets, and folding devices for folding the longer sheets in one direction and for folding the collected shorter sheets in the other direction.
- 50 55 10. A sheet handling machine including in combination means for directing longer and shorter sheets, collecting devices adapted to collect a larger number of shorter sheets and means for folding the various sizes of sheets to give all cut edges except at the fold.
- 55 60 11. A sheet handling machine including in combination means for directing longer and shorter sheets, collecting devices adapted to collect a larger number of shorter sheets, and folding devices for folding the longer sheets in one direction and for folding the shorter sheets in another direction.
- 65 12. A sheet handling machine including in combination means for cutting from a web single and double length sheets, means for collecting a double number of single length sheets, and folding devices for folding either length sheets to give all cut edges except at the fold.
- 70 13. A sheet handling machine including in combination means for cutting from a web single and double length sheets, means for collecting a double number of single length sheets, and folding devices for folding the long sheets in one direction and the short sheets in another direction.
- 75 14. A sheet handling machine including in combination means for cutting from a web single and double length sheets, collecting devices for collecting long sheets or a double number of short sheets, and folding devices for folding either length sheets to give all cut edges except at the fold.
- 80 85 15. A sheet handling machine including in combination means for cutting from a web single and double length sheets, collecting devices for collecting long sheets or a double number of short sheets, and folding devices for folding the long sheets in one direction and the short sheets in another direction.
- 90 95 16. A sheet handling machine including in combination means for supplying sheets of either single or double length, means for directing the sheets of one length to folding means and means for collecting the sheets of another length, folding means for receiving and folding the collected sheets.
- 100 105 17. A sheet handling machine including in combination means for supplying sheets of either single or double length, means for directing the sheets of one length to folding means and means for collecting the sheets of another length, folding means for receiving and folding the collected sheets.
- 110 115 18. A sheet handling machine including in combination means for supplying sheets of either single or double length, means for directing the sheets of one length to one collecting and folding mechanism and sheets of another length to another collecting and folding mechanism.
- 120 125 19. A sheet handling machine including in combination means for cutting a web into sheets of different lengths, means for directing said sheets along a path, a plurality of folding mechanisms, one folding mechanism being located at one side of said pathway and another folding mechanism on the opposite side of said pathway, and means for directing sheets of one length from said pathway to one of said folding mechanisms and for directing sheets of another length to another of said folding mechanisms.
- 125 130 20. A sheet handling machine including in combination means for supplying sheets

- 6 of either single or double length, means for directing the sheets of one length to one collecting and folding mechanism and sheets of another length to another collecting and folding mechanism, one folding mechanism folding transversely of the sheet and the other folding mechanism folding longitudinally of the sheet.
- 10 21. A sheet handling machine including in combination means for cutting from a web either single or double length sheets, means for directing the sheets of one length to folding means and means for collecting the sheets of another length, folding means for receiving and folding the collected sheets.
- 15 22. A sheet handling machine including in combination means for cutting from a web either single or double length sheets, means for directing the sheets of one length to one collecting and folding mechanism and sheets of another length to another collecting and folding mechanism.
- 20 23. A sheet handling machine including in combination means for cutting from a web either single or double length sheets, means for directing the sheets of one length to folding means and means for collecting the sheets of another length and delivering the collected sheets unfolded to folding means to be folded, one folding mechanism folding transversely of the sheet and the other folding mechanism folding longitudinally of the sheet.
- 25 35. 24. A sheet handling machine including in combination means for supplying sheets of different lengths, means for collecting a single group of sheets of one length, means for collecting a plurality of groups of sheets of a different length, means for folding sheets of one length longitudinally, means for folding sheets of another length transversely.
- 30 40. 25. A sheet handling machine including in combination means for cutting from a web sheets of different lengths, means for collecting a single group of sheets of one length, means for collecting a plurality of groups of sheets of a different length, means for folding sheets of one length longitudinally, means for folding sheets of another length transversely.
- 35 50. 26. A sheet handling machine including in combination means for supplying sheets of different lengths, means for collecting a single group of sheets of one length, means for collecting a plurality of groups of sheets of a different length, and a separate folder for each of said collecting means.
- 40 60. 27. A sheet handling machine including in combination means for cutting sheets of different length from a web, a cylinder proportioned to collect sheets with the pages printed lengthwise of the web, a cylinder proportioned to collect sheets with the pages
- 45 55. 65. printed across the web, and devices for folding either product.
- 50 70. 28. A sheet handling machine including in combination means for cutting sheets of different length from a web, a cylinder proportioned to collect sheets with the pages printed lengthwise of the web, a cylinder proportioned to collect sheets with the pages printed across the web, and folding means for transversely folding one length of sheets and folding means for longitudinally folding the other length of sheets.
- 55 75. 29. A sheet handling machine including in combination means for cutting sheets of different length from a web, a cylinder proportioned to collect sheets with the pages printed lengthwise of the web, a cylinder proportioned to collect a plurality of groups of sheets with the pages printed across the web, and devices for folding either product.
- 60 80. 30. A sheet handling machine including in combination means for cutting sheets of different length from a web, a cylinder proportioned to collect sheets with the pages printed lengthwise of the web, a cylinder proportioned to collect a plurality of groups of sheets with the pages printed across the web, and folding means for transversely folding one length of sheets, and folding means for longitudinally folding the other length of sheets.
- 65 85. 31. A sheet handling machine including in combination means for cutting sheets of different length from a web, two cylinders either of which is adapted to receive the cut sheets, means for folding longitudinally the sheets received by one cylinder and means for folding transversely the sheets received by the other cylinder.
- 70 90. 32. A sheet handling machine including in combination means for cutting sheets of different length from a web, two cylinders of different diameters either of which is adapted to receive the cut sheets, means for folding longitudinally the sheets received by one cylinder, and means for folding transversely the sheets received by the other cylinder.
- 75 95. 33. A sheet handling machine including in combination means for cutting sheets of different length from a web, two cylinders of different diameters either of which is adapted to collect the cut sheets, means for folding longitudinally the sheets received by one cylinder and means for folding transversely the sheets received by the other cylinder.
- 80 100. 34. A sheet handling machine including in combination means for cutting sheets of different length from a web, two cylinders adapted to collect the cut sheets, and one adapted to collect a plurality of the cut sheets about its circumference, means for longitudinally folding the sheets received by one cylinder, and means for transversely

- 5 folding the sheets received by the other cylinder.
35. A sheet handling machine including in combination means for cutting sheets of different length from a web, a cylinder for receiving sheets of a given length, traveling folding blade and folding jaws for folding the sheets transversely from off said cylinder, a second cylinder for receiving sheets 10 of a different length and a folder for longitudinally folding the collected sheets, and means for forwarding the collected sheets from said second cylinder to said last mentioned folder.
- 15 36. A sheet handling machine including in combination means for cutting sheets of different length from a web, a collecting cylinder for collecting sheets of a given length, traveling folding blade, and folding 20 jaws for folding the sheets transversely from off said cylinder, a second collecting cylinder for collecting sheets of a different length and a folder for longitudinally folding the collected sheets, and means for forwarding the collected sheets from said 25 second collecting cylinder to said last mentioned folder.
37. A sheet handling machine including in combination means for cutting sheets of different length from a web, a collecting cylinder 30 for collecting sheets of a given length, a folding blade mounted on said cylinder and rotating folding jaws coöperating therewith for folding the sheets transversely 35 from off said cylinder, a second collecting cylinder for collecting sheets of a different length and a folder for longitudinally folding the collected sheets, and means for forwarding the collected sheets from said second collecting cylinder to said last 40 mentioned folder.
38. A sheet handling machine including in combination a collecting cylinder having a given proportion to pages arranged along the plate cylinder of the press, a collecting 45 cylinder having a given proportion to pages arranged around the plate cylinder of the press, means for cutting sheets of different and corresponding lengths from the
- 50 web, and directing one length of sheet to one collecting cylinder and another length of sheet to the other collecting cylinder, means for folding one length of sheet transversely and means for folding the other length of sheet longitudinally. 55
39. A sheet handling machine including in combination means for supplying unfolded sheets of either single or double length, means for directing the sheets of one length to folding means and means for collecting 60 the sheets of another length and folding means for receiving and folding the collected sheets.
40. A sheet handling machine including in combination means for supplying unfolded sheets of either single or double length, means for directing the sheets of one length to folding means and means for collecting 65 the sheets of another length, and folding means for receiving and folding the collected sheets. 70
41. A sheet handling machine including in combination means for cutting from a web either single or double length sheets, means for directing the unfolded sheets of one length to folding means and means for collecting the unfolded sheets of another length, and folding means for receiving and folding the collected sheets. 75
42.
